UNITED STATES PATENT OFFICE.

ERNEST F. COLDWELL, OF LACHINE, QUEBEC, CANADA, ASSIGNOR TO ARTHUR L. CLEMENTS, OF TORONTO, ONTARIO, CANADA.

ORE-SEPARATOR.

1,363,760.

Specification of Letters Patent. Patented Dec. 28, 1920.

Original application filed March 9, 1917, Serial No. 153,756. Divided and this application filed May 28, 1917. Serial No. 171,557.

To all whom it may concern:

Be it known that I, ERNEST F. COLDWELL, a citizen of the United States, at present residing in the city of Lachine, in the Province 5 of Quebec and Dominion of Canada, have invented certain new and useful Improvements in Ore-Separators, of which the following is a full, clear, and exact description.

This invention relates to improvements in a method of and apparatus for separating gold, platinum or other metals from sand, pulverized rock, earth or the like, and is a division from my former application, Serial Number 153,756, filed March 9th, 1917.

The object of the invention is to provide a simple and efficient apparatus for separating and retaining the gold particles at a minimum expense for both plant and operating costs.

The apparatus consists briefly of a hopper containing the material to be treated, from which the material flows by gravity through a plurality of spouts in opposition to water jets. The material and water then fall through passages, in which they are subjected to the action of steam jets and are projected into cups containing amalgam. The greater part of the gold is caught in the cups and retained by the amalgam, while the sand is carried out by the water. Any small amount of gold which adheres to or is carried out with the sand is caught in mercury cups in a screening device below. The mercury catches in addition to gold, any particles of amalgam which may have been carried out of the cups by the sand. The screening device consists of a series of trays, which are agitated by suitable means, and which each contain a separately agitated screen, for the purpose of better separating any particles of gold or amalgam which may be adhering to the sand.

In the drawings which illustrate the invention:—

Figure 1 is a front elevation of the device, partly in section.

Fig. 2 is a side elevation of same.

Fig. 3 is a section on the line 3—3 of Fig. 1, showing the arrangement of amalgam cups.

Fig. 4 is a plan view of one of the trays, showing the screen therein.

Referring more particularly to the drawings, 11 designates a hopper adapted to contain the material, having the bottom thereof provided with grooves or corrugations 12. The bottom is also inclined transversely to the grooves, and at the lower edge, each groove terminates in a spout 13, which spouts deliver the material to funnels 14 set in the mouths of the passages 15, and terminating opposite the view openings 16, so that the feed of material from each spout may be observed. A water pipe 17 leads into each spout 13, and is arranged to direct a jet of water against the overflowing material. This water flows up in each groove a certain distance, keeps the material stirred up, and then flows down in the bottom of the groove along with the material, and discharges through the funnel 14 into the passage 15. Each passage 15 is provided with a pipe 18 projecting thereto and having a down-turned bell mouth 19. These pipes blow steam or air down along with the falling material and water, and operate to further break up any lumps which may remain. The jets also give velocity to the material and water, so that they discharge with considerable violence from the passages 15 into the amalgam cups 20. These cups 20 rest in a rack 21 in a chamber 22, and are each provided near the top with an inwardly projecting lip 23 designed to prevent as far as possible the escape of gold or amalgam from the cup. The velocity of the material entering the cup keeps the fine grains of material practically in suspension in the water, so that as the water flows out over the rim of the cup, the earthy matter is carried with it, while the heavier gold is retained in the cup by the force of gravity and by the amalgam. The water and earthy material, together with such particles of gold as have not been separated, and any particles of amalgam which have escaped from the cups, flow out of the chamber through the descending passage 24, at the discharge end of which is an annular apertured water pipe 25 arranged to direct a jet of water downwardly around the mouth of the pas-

sage 24. This curtain of water acts as a condenser for any steam which may remain in vaporous form in the apparatus, and also provides additional water to agitate and 5 wash the material on the trays 26 and 27.

These trays are suspended one above the other by means of links 28 and 29 from fixed frame or other members 30 and may be agitated by any suitable means, such as the 10 eccentric devices 31. Each of the trays or pans is slightly sloped toward the center, where sumps or depressions 32 and 33 are formed, which may be filled with mercury for the purpose of catching and holding any 15 particles of gold or amalgam that may have escaped from the apparatus above. The upper tray 26 is provided with a peripheral flange or wall, which is slightly lower at the ends 34 than at the sides 35, so that all 20 escape of material will be at the ends of the tray. The lower tray 27 may be formed similarly or may have its flange of uniform height all around. In the bottom of each 25 tray, a screen 36 is provided, which has slight movement independent of the trays. Each screen is suspended by a single member 37 at each end, as distinguished from the links 28 and 29 attached to the sides of the trays. The screens may be agitated by 30 an eccentric device 38, similar to that used for agitating the trays, but arranged to move the screens in the opposite direction to the trays, and preferably at a higher speed. The higher screen speed may be obtained 35 by giving the eccentric device greater throw as shown, or by any other suitable means. It will be clearly seen in Fig. 2 that the suspension members of the screens are attached on opposite sides of the center 40 line, so that in addition to the agitation imparted by the eccentric devices, the screens will have a slight oscillatory movement in a horizontal plane. If desired, the screen may be given in addition a buckling 45 motion, as indicated in dotted lines, Fig. 1, by limiting the movement of one suspension link, so that it checks the end of the screen, which it supports, while the opposite end connected to the eccentric device continues 50 to move. It will be understood, however, that this buckling or bending of the screen may be downward as well as upward, or may be dispensed with altogether. The limitation of movement of the suspension 55 link may be effected by means of a friction joint or in any other manner found suitable.

The amount of water and steam necessary to produce proper movement and separation

of the particles may be regulated by means of valves 39. The cups 20 may be lifted out 60 of their supporting rack by opening the door 40, provided for that purpose in the wall of the chamber 22. The trays 26 and 27 together with the screen contained in them may also be removed for the purpose 65 of clearing the sumps or cups 32 and 33. While gold is the only metal mentioned in the description as reclaimable by the apparatus, it will be understood that the invention is in no way limited to this particular 70 metal, as platinum and possibly other metals may be separated by the same or a very similar apparatus from sand and earthy matter with which they are mixed. It will be understood that air or other fluid may be 75 used instead of steam to assist in breaking up lumps of the material by dashing them against the sides of the passages 15 and into the amalgam cups.

Having thus described my invention, what 80 I claim is:—

1. In a device of the class described, a tray, a screen therein, means for moving the tray, and means for producing a compound movement of the screen, said movement being partly in the line of tray movement, 85 partly oscillatory in a horizontal plane and partly a vertical movement.

2. In a device of the class described, a tray, a screen therein, means for moving the 90 tray and means for moving the screen, means for resisting the movement of said screen, whereby the screen will be buckled, said screen moving and screen movement resistance means being arranged out of alignment 95 relatively to the direction of screen movement, whereby the screen is oscillated about a point within its periphery simultaneously with the other movements thereof.

3. In a device of the class described, a 100 tray, means for moving the tray, a screen in the tray, and means attached to one edge of the screen for moving the same relatively to the tray in substantially the plane of tray movement, a suspension member for the 105 screen attached to the opposite edge thereof from the moving means and arranged to limit movement of the screen edge to which it is attached to a degree less than the movement imparted by the screen moving 110 means, whereby the screen will be buckled relatively to the plane of the tray.

In witness whereof, I have hereunto set my hand.

ERNEST F. COLDWELL.
